CLAIM

The ornamental design for a tuning peg pendant, as shown and described.

DESCRIPTION

FIG. 1 is a front perspective view of a first embodiment of a tuning peg pendant showing my new design;
FIG. 2 is a front perspective view thereof shown in an environment of use;

FIG. 3 is a front elevational view thereof;

FIG. 4 is a right side elevational view thereof, the left side elevational view being identical thereto;

FIG. 5 is a top plan view thereof;

FIG. 6 is a bottom plan view thereof;

FIG. 7 is a front perspective view of a second embodiment of a tuning peg pendant showing my new design;

FIG. 8 is a front perspective view thereof shown in an environment of use;

FIG. 9 is a front elevational view thereof;

FIG. 10 is a right side elevational view thereof, the left side elevational view being identical thereto;

FIG. 11 is a top plan view thereof;

FIG. 12 is a bottom plan view thereof;

FIG. 13 is a front perspective view of a third embodiment of a tuning peg pendant showing my new design;

FIG. 14 is a front perspective view thereof shown in an environment of use;

FIG. 15 is a front elevational view thereof;

FIG. 16 is a right side elevational view thereof, the left side elevational view being identical thereto;

FIG. 17 is a top plan view thereof;

FIG. 18 is a bottom plan view thereof;

FIG. 19 is a front perspective view of a tuning peg pendant showing my new design;

FIG. 20 is a front perspective view thereof shown in an environment of use;

FIG. 21 is a front elevational view thereof;

FIG. 22 is a right side elevational view thereof, the left side elevational view being identical thereto;

FIG. 23 is a top plan view thereof; and,

FIG. 24 is a bottom plan view thereof.

(Continued)

The broken lines on the surface of the pendant represent portions of the tuning peg pendant which form no part of the claimed design. The broken lines showing a chain in FIGS. 2, 8, 14 and 20 illustrate environment and also form no part of the claimed design.

1 Claim, 12 Drawing Sheets

Related U.S. Application Data

No. 29/484,255, filed on Mar. 7, 2014, now Pat. No. Des. 770,563, which is a continuation of application No. 13/466,080, filed on May 7, 2012, now abandoned.
